CLAIM

The ornamental design for a combination cup and insulating sleeve, as shown and described.

DESCRIPTION

FIG. 1 is a perspective view of a design of a combination cup and insulating sleeve;

FIG. 2 is a left side elevational view thereof (the right side, front and rear elevational views thereof are identical images of the view shown in FIG. 2);

FIG. 3 is a top plan view thereof; and,

FIG. 4 is a bottom plan view thereof.

The broken lines are shown for the purpose of illustrating parts of the article that form no part of the claim.
